UNITED STATES PATENT OFFICE

92,664

DESIGN FOR A CLOTHESPIN NOVELTY

Marie F. Lonier, La Grange, Ill.

Application April 6, 1934, Serial No. 51,325

Term of patent 7 years

To all whom it may concern:

Be it known that I, MARIE F. LONIER, a citizen of the United States, residing at La Grange, in the county of Cook and State of Illinois, have invented a new, original, and ornamental Design for a Clothespin Novelty, of which the following is a specification, reference being had to the accompanying drawing, forming part thereof.

Fig. 1 is a front elevation of a clothespin novelty showing my new design; and

Fig. 2 is a side elevation of the same.

The design is a common clothespin painted either in black and white or in colors in such manner that the rounded top of the clothespin

becomes the head, the midsection the body, and the split section the legs of a fanciful personage or mannikin figure, which may represent different period styles or different occupations or nationalities. The arms are of fabric covered wire as shown. The hats are formed from the crowns of acorns from which the nuts have been removed, and suitably painted in colors to match the rest of the costume. The clothespins are supported on the ornamental standard as shown.

What I claim is:

The ornamental design for a clothespin novelty, as shown and described.

MARIE F. LONIER.
